M. E. NEENAN.

SHEAVE,

FILED AUG. 17, 1921.

Fig. 2.

Inventor
By his Attorney Michael E. Neenan
Warren S. Ashley

UNITED STATES PATENT OFFICE.

MICHAEL E. NEENAN, OF NEW YORK, N. Y., ASSIGNOR TO NEENAN ELEVATOR CORPORATION, A CORPORATION OF NEW YORK.

SHEAVE.

Application filed August 17, 1921. Serial No. 492,896.

To all whom it may concern:

Be it known that I, MICHAEL E. NEENAN, a citizen of the United States, and a resident of the city of New York, in the county 5 of New York and State of New York, have invented certain new and useful Improvements in Sheaves, of which the following is a specification.

The invention relates to improvements in 10 sheaves applicable to elevator utilities, having associated therewith a radially disposed fiber peripheral traction tread arranged to receive ropes and cables of any material which latter forms their own grooves on 15 frictional engaging surfaces.

One object of the invention is the providing of a peripheral traction tread for sheaves or like articles of manufacture, made up of a plurality of twisted tarred fiber portions 20 or other like material radially disposed with relation to the axis of the sheave, and permanently pressed into position upon the reception drum of said sheave by means of a locking or clamping plate in order to insure 25 an increased traction gripping and wear resisting surface.

Another object of the invention resides in the fact, that by providing a traction tread of the type as set forth, that cables and other 30 like units of sustenance, wear or cut their own grooves or channels therein, and by reason of the difference in material, retard wear and injury to the engaging faces of the units, and further a traction tread that 35 when worn out, and requiring readjustment, such parts may be discarded and an entire new tread supplied at very little cost and trouble.

In the following is described in connection 40 with the accompanying drawings, one embodiment of the invention, the features thereof being more practically pointed out hereinafter in the claims.

In the drawings, Fig. 1 is an end view of 45 a sheave part thereof being shown in vertical sectional view illustrating the invention after the grooves have been cut therein by reason of the engagement therewith of cables, ropes, etc.; Fig. 2 is a detail vertical 50 sectional view of the sheave and fiber frictional tread illustrating the disposition of the units of material comprised in said tread and Fig. 3 is an elevation of a sheave part of its edge being broken away to show the

peripheral tread of fibrous material applied 55 thereto.

Similar numerals of reference indicate similar parts throughout the several views.

In the drawings 1 designates the body of a sheave comprising a sleeve core 2 having 60 formed therein an aperture 3 arranged to receive a shaft and a series of spokes 4 carrying at their outer ends a female drum 5 provided at its edge with a channeled shoulder 6. The inner wall of shoulder 6 is tapered 65 inwardly at 7 to form a reception housing for the peripheral fiber tread.

8 indicates a locking plate provided with a channeled shoulder 9 and a tapering wall 10 to form the outer side of the sheave channel 11.

12 designates a multiplicity of fiber rope ends, set on their respecting ends on the housing formed by the female drum 5 and the tapered inner walls 7 and 10 of the cable 75 housing or channel 11, and when said fiber ends are properly disposed thereon, a series of bolts 13 are inserted in holes 14 and nuts 15 placed thereon, and the plate 8 is forced inwardly to a proper tension, 80 the compression created by seating said locking plate 8 causes the fibrous fillers to become a compact hardened tractional tread, with a flush wear resisting surface 16. Said surface 16 within channel 11 is depressed 85 between the respective shoulders of the sheave, thereby providing guides for the units operative connection therewith. The action on said tread by cables, ropes or sheave actuating units, form in said peripheral tread grooves 17 in which said units run until the fibrous filler is worn out or destroyed, at which time an entire new tread 90 may be inserted with a minimum of time and expense.

The invention may be varied in many ways, and diverse materials may be used, without departing from the general spirit of the invention.

What is claimed and desired to secure by 100 Letters Patent of the United States is:

1. A device of the character described comprising a sheave supporting body, a reception drum formed thereon, a series of twisted tarred rope ends set radially to the 105 axis of said drum adapted to form a peripheral traction tread therefor, and a locking plate mounted on said drum and engag-

ing said traction tread arranged to hold said tread in position thereon.

2. A device of the character described including a peripheral traction tread for 5 sheaves, comprising a plurality of twisted tarred rope ends disposed radially with relation to the axis of said sheave, a reception drum formed on said sheave adapted to receive said tread, and a locking plate mount-

ed on said drum and engaging said tread adapted to compress said tread into substantially a solid fibrous mass into which a plurality of cables may form a plurality of grooves.

Signed at New York city, in the county of 15 New York and State of New York this 12th day of August A. D. 1921.

MICHAEL E. NEENAN.
